UNITED STATES PATENT OFFICE.

THOMAS H. KANE, OF YOUNGSTOWN, OHIO.

HANGER.

Application filed September 9, 1920. Serial No. 409,233.

To all whom it may concern:

Be it known that I, THOMAS H. KANE, of Youngstown, Ohio, a citizen of the United States of America, residing at Youngstown, 5 in the county of Mahoning and State of Ohio, have invented certain new and useful Improvements in Hangers, of which the following is a specification.

This invention relates to a hanger adapted to support or carry fixtures or other apparatus from a floor, wall, ceiling or other supporting surface.

The object of the invention is to provide a hanger which may be permanently mounted 15 or embedded in the structure of the wall, ceiling or the like at the time said wall or ceiling is formed so that it becomes in effect a permanent integral part of the wall or ceiling so as to provide a very strong and 20 efficient support for the fixtures or other apparatus while at the same time presenting a very neat and finished appearance and permitting ready mounting of the fixtures or other apparatus thereon.

25 In its preferred form the invention comprises an inverted substantially U-shaped member of considerable length having in-turned flanges at its lower portion which are cut away at a suitable point or points 30 in the length of the hanger to permit a bolt or other headed member carried by the fixture or apparatus to be engaged above the flanges and to be supported at any suitable 35 position thereby, said U-shaped member having upwardly extending, preferably inclined and bent over, prongs which when the member is embedded in the concrete or other material of the supporting surface effectively prevent the member from being pulled 40 out and serve to sustain material loads.

The invention is illustrated in the preferred form in the accompanying drawings, in which:—

Figure 1 is a view showing the hanger 45 embedded in the concrete or other material of a ceiling structure;

Figure 2 is an enlarged view, partly in section, of a portion of the hanger;

Figure 3 is a section taken on the line 3—3 50 of Figure 2 and looking in the direction of the arrows; and

Figure 4 is an underneath view of a portion of the hanger shown in Figure 2.

Referring more particularly to Figure 1, 55 the hanger therein shown comprises a member 1 which is preferably of considerable

length and is embedded in the concrete or other material of the ceiling structure 2 so that its lower surface is substantially flush with the lower surface of the ceiling structure. The member 1 is provided with a plurality of upstanding prongs 3 which are preferably, although not necessarily, arranged at opposite sides of the member. 60 As indicated in the figure, the prongs at one side of the member 1 are all inclined to the vertical in one direction while the prongs at the other side of the member are all inclined to the vertical in the opposite direction, the prongs at one side being staggered relatively to the prongs at the other side as is indicated by the full lines and dotted lines in the figure. Each of the prongs is shown as bent over at 4 at its upper end so as to form in effect a hook 65 embedded in the concrete structure. It is, of course, to be understood that while the arrangement of the prongs illustrated is preferable, the invention is not confined thereto as good results are obtainable by the use 70 of inclined prongs which are not bent over at their upper end and, similarly, the bent over prongs need not necessarily be inclined in the manner indicated. If desired, in the case of extra heavy loads transverse rods as indicated at 5 may be embedded in the concrete beneath the bent over upper ends 4 of the prongs, these rods adding materially 75 to the strength of the structure.

Referring now more particularly to Figures 2, 3 and 4, it will be seen that the body member 1 is of inverted substantially U-shaped form, having inwardly extending flanges 6 extending throughout the entire length of the member excepting that at one or more suitably located points the flanges are cut away at 7 (Figures 2 and 4) to provide an opening 8 through which may be passed the head of the bolt or other headed member carried by or secured to the article, fixture or apparatus to be supported by the hanger. By passing this headed member through the opening 8 and moving the same longitudinally to bring the head over the flanges 6 the fixture or apparatus may be supported at any desired point in the length 90 of the hanger.

The member 1 is also shown as initially provided with outwardly extending flanges 9 from which the prongs 3 are formed by shearing a desired length of the flange away 95 from the corresponding side wall of the

body member and first bending this sheared portion upwardly into the inclined position indicated in the figures and then bending the upper end over to form the hooked portion 4. A suitable length of the flange 9 is left unsheared, as indicated at 10, so that each prong remains integral with the side wall of the hanger member.

It is preferred to form the member 1 from a plate of I section, as indicated in dot and dash lines at 11 in Figure 3, the web of this plate being bent along two spaced longitudinal lines to form the web and side walls of the U-shaped member, the flanges at opposite sides of the I section plate forming the inwardly and outwardly extending flanges of the U-shaped member 1. The invention is not, however, restricted to this manner of forming the hanger.

While, as above stated, the prongs may be variously arranged upon the member 1 to co-act with the concrete or other material in supporting the member, it is preferred to arrange these prongs in the manner illustrated most clearly in Figure 2, in which the prongs at one side of the member are staggered in relation to the prongs at the other side of the member, the upper ends of the prongs overlapping, as by this means a member of considerable length may, if desired, be cut into smaller sections each of which contains one or more pairs of prongs arranged in such relation on the cut section as to most efficiently support the section from the ceiling or other structure and to uniformly distribute the load.

It will be understood from what has been said that the hanger comprising the body member 1 and the prongs carried thereby is placed in position during the formation of the wall, floor or ceiling structure, and the concrete or like material will flow in, around and under the various portions of the hanger, and when it has set or hardened will form such a strong support that the hanger will carry material loads. The use of the rods 5 embedded in the concrete beneath the hooked portions of the prongs will add material strength to the structure and enable much heavier loads to be supported. The formation of the prongs as integral parts of the body member also tends to add strength to the structure as the prongs cannot become detached from, or break away from, the hanger proper. The flanged portions of the member 1 which forms the flanges 6 and 9 upon which the apparatus is supported and from which the prongs are formed are preferably made heavier than the web portion of the body member.

It is preferred to close each open end of the body member 1 by an end cap or plate 12 indicated in dotted lines at the left hand end of Figure 2, which plate approximately fits the interior of the body member 1

and is set in a short distance so that the concrete flows around the end of said member 1 against the cap and further assists in supporting the hanger in place.

As already indicated, it is not desired to restrict the invention to the particular details of construction hereinbefore set forth as the same may be changed in various ways without departing from the spirit of the invention.

It is also desired to point out that whereas for convenience reference has been made in the foregoing description, and will be made in the appended claims, to the flanges 6, or to the slot which receives the bolt or like member, being located at the lower portion of the body member 1 and the prongs as upstanding from said body member, it is not desired to limit the invention in this respect as the invention also contemplates the use of the hanger in connection with a vertical wall or in connection with a floor or any other supporting surface.

What I claim as my invention and desire to secure by Letters Patent is:—

1. A hanger of the class described, comprising a hollow member having a slot in its lower wall of less width than the interior distance between its side walls, and provided at opposite sides throughout the length thereof with upstanding inclined prongs of which those at one side are inclined oppositely to those at the other side of the member for the purpose specified.

2. A hanger of the class described, comprising a hollow member having a slot in its lower wall of less width than the interior distance between its side walls, and provided throughout the length thereof with upstanding prongs, said lower wall having at a suitable point in its length an opening of substantially the same width as the distance between said side walls, for the purpose specified.

3. A hanger of the class described, comprising an inverted substantially U-shaped member having inwardly directed flanges at its lower portion and initially provided with outwardly directed flanges at said lower portion, parts of which flanges are sheared through and bent upwardly to provide upstanding prongs of which those at one side of the member are oppositely inclined to those at the other side of the member for the purpose specified.

4. A hanger of the class described, comprising an inverted substantially U-shaped member having inwardly directed flanges at its lower portion, and provided throughout the length thereof and at opposite sides of the longitudinal center line thereof with two series of upstanding prongs, said flanges being cut away at a suitable point in the length thereof for the purpose specified.

5. The combination with a supporting surface of concrete or like material, of a hanger embedded in said material and comprising a body member having a longitudinal slot in its lower exposed portion and a plurality of upstanding prongs at opposite sides of said member, the prongs at one side being inclined oppositely to those at the other side of the member. 5
- 10 6. The combination with a supporting surface of concrete or like material, of a hanger embedded in said material and comprising a body member having a longitudinal slot in its lower exposed portion and a plurality of upstanding prongs bent over at their upper ends, and a plurality of transverse rods embedded in said material beneath the bent over ends of the prongs. 15
- 20 7. A hanger of the class described, comprising a hollow member having an unobstructed passageway extending longitudinally therethrough, and having a longitudinally extending unobstructed slot in one wall thereof communicating with said passageway, and of less width than said passageway, said member being provided throughout the length thereof with two series of upstanding anchoring prongs at opposite sides of the longitudinal center line thereof, all for the purposes herein specified. 25
- 30 8. A hanger of the class described, comprising a hollow member having an unobstructed passageway extending longitudinally therethrough, and having a longitudinally extending unobstructed slot in one wall thereof communicating with said passageway, and of less width than said passageway, said member being provided throughout the length thereof with upstanding anchoring prongs inclined in the direction of the length of the member, all for the purposes herein specified. 35
- 40 9. A hanger of the class described, comprising a hollow member having an unobstructed passageway extending longitudinally therethrough, and having a longitudinally extending unobstructed slot in one wall thereof communicating with said passageway, and of less width than said passageway, said member being provided throughout the length thereof with upstanding anchoring prongs bent over at their upper ends, all for the purposes herein specified. 45
- 55 10. A hanger of the class described, comprising an inverted substantially U-shaped member having substantially parallel side walls providing an unobstructed passageway extending longitudinally through said member, and having inwardly directed flanges at the lower ends of said side walls providing an unobstructed slot communicating with said passageway, of less width than said passageway, said member being provided throughout the length thereof with 60
- two series of upstanding anchoring prongs at opposite sides of the longitudinal center line thereof, all for the purposes herein specified. 65
11. A hanger of the class described, comprising an inverted substantially U-shaped member having substantially parallel side walls forming an unobstructed passageway extending longitudinally through said member, and having inwardly directed flanges at the lower ends of said side walls providing an unobstructed slot communicating with said passageway and of less width than said passageway, said member being initially provided at the lower ends of said side walls with outwardly directed flanges, parts of which are sheared through and bent upwardly to provide upstanding anchoring prongs, all for the purposes herein specified. 70
12. A hanger of the class described, comprising an inverted substantially U-shaped member having substantially parallel side walls forming an unobstructed passageway extending longitudinally through said member, and having inwardly directed flanges at the lower ends of said side walls providing an unobstructed slot communicating with said passageway, and of less width than said passageway, said member being initially provided at the lower ends of said side walls with outwardly directed flanges, parts of which are sheared through and bent upwardly to provide upstanding anchoring prongs bent over at their upper ends, all for the purposes herein specified. 80
13. The combination with a supporting surface of concrete or like material, of a hanger embedded in said material and comprising a hollow body member having an unobstructed passageway extending longitudinally therethrough, and having a longitudinally extending unobstructed slot in the lower exposed wall of said member communicating with said passageway and of less width than said passageway, said body member having at opposite sides of the longitudinal center line thereof two series of upstanding prongs anchored within said material. 90
14. The combination with a supporting surface of concrete or like material, of a hanger embedded in said material and comprising a hollow body member having an unobstructed passageway extending longitudinally therethrough, and having a longitudinally extending unobstructed slot in the lower exposed wall of said member communicating with said passageway and of less width than said passageway, said body member having a plurality of upstanding prongs anchored within said material and inclined in the direction of the length of said body member. 100
